CLAIM

The ornamental design for a bracket for weight rack, as shown and described.

DESCRIPTION

FIG. 1 is a bottom, front, right perspective view of a first embodiment of a bracket for weight rack showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom, rear, left perspective view of a second embodiment of a bracket for weight rack showing my new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines immediately adjacent to the shaded area define the bounds of the claimed design and form no part thereof. The broken lines depicting the remainder of the bracket for weight rack and the exemplary environment show features that form no part of the claimed design.
